BASE FOR MOTOR PUMP-EQUIPPED SIGN CLEANER

Thomas J. McMullen, 5529 Park Ave., Minneapolis, Minn.

Filed Nov. 18, 1963, Ser. No. 77,457

Term of patent 14 years

(Cl. D55—1)

FIG. 1

FIG. 3

FIG. 1 is a view in perspective showing the top, front and one side, the opposite side thereof being identical and consequently not shown;

FIG. 2 is a view in bottom plan; and

FIG. 3 is a view in rear elevation on a reduced scale.

I claim:

The ornamental design for a base for motor pump-equipped sign cleaner, as shown and described.
